UNITED STATES PATENT OFFICE.

RALPH A. SCHOENBERG, OF BRANCHPORT, NEW JERSEY.

DESIGN FOR A PIPE-BOWL.

45,208.

Specification for Design.

Patented Feb. 3, 1914.

Application filed June 28, 1913. Serial No. 776,444. Term of patent 14 years.

To all whom it may concern:

Be it known that I, RALPH A. SCHOENBERG, a citizen of the United States, residing at Branchport, in the county of Monmouth and State of New Jersey, have invented a new, original, and ornamental Design for Pipe-Bowls, of which the following is a specification, reference being had to the accompanying drawing, forming part thereof.

Figure 1 is an elevation of a pipe bowl showing my new design; and Fig. 2 is a

plan of the same. Fig. 3 is a view looking into the stem of the pipe bowl from the right hand side of Fig. 1; and Fig. 4 is a perspective view of the pipe bowl.

What I claim is:

The ornamental design for a pipe bowl as shown.

RALPH A. SCHOENBERG.
